(57) **CLAIM**

The ornamental design for a container for stick fragrance diffusers, as shown and described.

DESCRIPTION

FIG. 1 is a front view of the container for stick fragrance diffusers of the present invention.

FIG. 2 is a plan view of the container of the present invention.

FIG. 3 is an oblique perspective view of the container of the present invention.

FIG. 4 is another oblique perspective view of the container of the present invention taken at a different angle than in FIG. 3.

FIG. 5 is another oblique perspective view of the container of the present invention taken at a different angle than in FIGS. 3 and 4; and,

FIG. 6 is a bottom view of the container of the present invention.

The broken lines shown in the drawings are for illustrative purposes only and form no part of the claimed design.

Any indicia shown in broken lines in the drawings form no part of the design to be patented. The container, which is shown to include two segments (i.e., an upper segment, and a lower segment), is designed so that the upper segment is transparent and the lower segment is opaque so that, as part of the design, the stick fragrance diffusers are visible through the transparent upper segment.
